James Hutchison, Troy N. Y., Assignor to Deborah Powers
A. E. Powers; & Nath'l Powers, Lansingburgh, N. Y. ~
Letters Patent No 371. Dated May 13. 1851

~~~~~  
The schedule referred to in these Letters Patent and making part of the same

~~~~~  
To all whom it may concern:

Be it known; that I, James
Hutchison of the City of Troy, County of Rensselaer and State

of New York, have invented and produced a new pattern design or figure to be printed or stamped upon floor oil Cloths, of which the following is a full and exact description viz:

The principal or leading objects in the pattern are two squares, laid diamondwise or diagonally upon the pattern and are each ornamented with representations of foliage and flowers or fruit, in plain colorings —

These squares are surrounded, and separated from each other, by two broad bands of dissimilar shades of color, which in their turn are separated from each other by a narrow line of deeper coloring.

These bands are also ornamented by objects representing curved work in an arabesque style: the whole effect of the pattern being that of two square tiles disposed diamondwise on the pattern with a square in the centre of each also disposed in the same manner; the general arrangement and details of the pattern being shewn upon the annexed drawing or copy which forms part of this specification

And what is claimed as my invention and desired to be secured by letters patent of the United States, is the arrangement of ornamental figures forming a design for floor oil Cloths, as shewn in the aforesaid drawing
